UNITED STATES PATENT OFFICE.

MAURICE A. HOFFT, OF INDIANAPOLIS, INDIANA, ASSIGNEE TO THE M. A. HOFFT COMPANY, OF INDIANAPOLIS, INDIANA, A CORPORATION OF INDIANA.

FURNACE.

1,255,832.

Specification of Letters Patent. Patented Feb. 5, 1918.

Application filed May 16, 1917. Serial No. 165,934.

To all whom it may concern:

Be it known that I, MAURICE A. HOFFT, a citizen of the United States, residing at Indianapolis, in the county of Marion and 5 State of Indiana, have invented a new and useful Furnace, of which the following is a specification.

The object of my invention is to provide 10 improvements in details of construction in that type of smokeless furnaces wherein the fuel is supported upon downwardly and rearwardly inclined grate bars and upwardly swinging feeder fingers, and the ash is delivered to downwardly and rearwardly 15 swinging plates, whereby the durability of the apparatus is materially increased.

The accompanying drawings illustrate my invention.

Figure 1 is a perspective view of the 20 interior of a furnace constructed in accordance with my invention, the setting being shown in partial section; Fig. 2 is a perspective view of my improved form of grate bar; Fig. 3 a perspective view of one of the plates 25 for embedment in the bridge wall to form a support for one of the ash plates; Fig. 4 a perspective view of one end of the bridge plate which supports the lower ends of the 30 grate bars; Fig. 5 a vertical section lengthwise of the furnace, the plane of the section being distorted at one point in order to show one of the feeder fingers in side elevation.

In the drawings, 10 indicates a downwardly and rearwardly inclined plate or 35 shelf extending across the front of the furnace setting 11. A bridge plate 12 is arranged in setting 11 so that its upper edge 13 will be in substantial alinement with the shelf 10 and this bridge plate is provided 40 with a forward surface 14, the purpose of which will appear. At each end the bridge plate 12 is provided with a laterally extended footing 15 designed to be embedded in the setting 11. Near each end and at the middle, 45 upon its rear face, the bridge plate 12 is provided with an upwardly extended hook or finger 16 which is spaced through the rear face of bridge plate 12, said hook forming a supporting pocket for the downwardly extended 50 finger 17 of an arm 18 which is designed to form a support for the ash plates 19, and of which several will be provided. Each arm 18 is provided at its rear end with a

vertical plate 20 and a horizontal plate 21 of such form that plate 20 may rest against 55 the forward face of the bridge wall 22, while plate 21 is embedded in, said bridge wall. Each arm 18 near plate 20 is provided in its upper surface with a downwardly and rearwardly inclined transverse groove or 60 pocket 23.

In the form shown in the drawings, there are two ash plates 19, each of which is slotted at various points, as indicated at 24, and each of which is provided at its rear 65 corners with a trunnion pin 25 adapted to seat in one of the grooves 23.

Each ash plate is provided with a downwardly extended arm 27, the lower end of which has pivoted, at 28, an operating link 70 29 which is extended upwardly and forwardly through the face plate 30 and formed in a common manner to support the ash plate normally in the position shown in full 75 lines in Fig. 5.

In devices of this general type, very considerable difficulty is experienced with the grate bars because, owing to the changes in temperature, they become warped and broken. By forming the grate bar in the 80 manner now to be described, I have eliminated to a very considerable degree this difficulty. My improved form of grate bar is shown in Fig. 2 comprises a foot plate 41 having at its under side a rabbet 42 which 85 will rest upon the upper edge of the bridge plate 12 formed by the surfaces 13 and 14. The footing plate 41 is carried at the lower end of a comparatively deep narrow rib or plate 43, the upper edge of which carries, 90 along its sides, a series of tapered separated teeth 44. The upper edge of plate 43 at suitable points is provided with downwardly and rearwardly inclined notches 45 which form pockets for the reception of the trunnions of feeder fingers to be described. At the upper end of plate 43, which is about half the total length of the grate bar, there 95 is a transverse wall 46 to which are connected two parallel walls 47, 47 having a depth substantially equal to the depth of wall 46. The walls 47 are set inwardly from the ends of wall 46 so as to leave shallow notches 48 at the edges of this portion of the grate bar. The walls 47 are connected by transverse 100 walls 49 which are preferably of the herring-

75

90

95

100

105

bone type, and these walls are separated by spaces 50 in a common manner. At their upper ends walls 47 are transversely thickened, as indicated at 51, corresponding to 5 the lateral extension of the wall 46 beyond walls 47. The lower faces of walls 47 at their upper ends, as indicated at 52, are smooth and flat so as to lie loosely upon shelf 10. By this arrangement, the weight of the 10 grate bars and the applied load is taken by the bridge plate 12 and shelf 10; the downward thrust is taken by surface 14 of bridge plate 12, and the bars are individually capable of free expansion and contraction upon 15 shelf 10. It will also be noted that the deep plates 43 will lie beneath the hottest portion of the fire wall, the shallower walls 47 connected by the herringbone cross bars 49 will lie beneath the less hot portions of 20 the fire wall. I have found in practice that this peculiar combination has resulted in a grate bar which has a very long life and retains its original shape.

When a plurality of grate bars such as 25 have been described are placed side by side, as shown in Fig. 1, it will be seen that spaces of considerable width are formed between the plates 43, while the spaces resulting from the registry of the notches 48 are only sufficient to permit free circulation of air without 30 permitting the unburned fuel to drop through. The spaces between the plates 43 are filled by pivoted feeder fingers 60, each of which is provided at its lower end with 35 oppositely projected trunnions 61 and also provided with a downwardly extending operating arm 62. The trunnions 61 are designed for reception in grooves 45 of plates 43. The main body of the finger 60 comprises 40 a pair of parallel side plates 63 substantially triangular in elevation. These side plates are connected at their upper edges by transverse grate bars 64 which are spaced apart to form air passages 65, and at their 45 rear ends are connected by an arc-shaped plate 66 which forms a closure for the space between the rear ends of the plates 63 so that, when a feeder finger is thrown upwardly, as shown in section in Fig. 5, to feed 50 the partially burned fuel downwardly along the grate bars, the plate 66 cut cleanly through the bed of fuel and prevent that portion of the bed of fuel lying upon the upper portion of the grate bars from sliding 55 downwardly until after the feeder finger has been returned to its normal position.

The operating arms 62 are connected to 60 links 66 which are extended forwardly through face plate 30 and attached to suitable operating levers 67. The particular manner in which the feeder fingers are to be operated forms no part of my present invention.

I claim as my invention:

65 1. In a furnace, the combination of a plu-

rality of grate bars each formed of a comparatively deep plate at its lower end and a pair of vertical walls at its upper end connected by cross bars, said vertical walls being connected by a cross wall with the upper end of the plate and the plate having notches in its upper edge to receive feeder finger trunnions, a plurality of feeder fingers mounted in the spaces between the deep plates of the grate bars and having trunnions pivotally supported in the notches of the grate bars, and means for swinging said feeder fingers. 70

2. In a furnace, the combination of a plurality of grate bars each formed of a comparatively deep plate at its lower end and a pair of vertical walls at its upper end connected by cross bars, said vertical walls being connected by a cross wall with the upper end of the plate and the plate having notches in its upper edge to receive feeder finger trunnions, and having at its lower end a transverse plate having a width exceeding the thickness of the deep plate, a plurality of feeder fingers mounted in the spaces between the deep plates of the grate bars and having trunnions pivotally supported in the notches of the grate bars, and means for swinging said feeder fingers. 80

3. As an article of manufacture, a grate bar comprising a comparatively deep vertical plate having a transverse notch in its upper edge, a transverse wall at the upper end of said plate and having a lateral extent exceeding the thickness of said plate, a pair 95 of parallel walls connected to the transverse wall and spaced apart a distance such that the distance between their outer faces exceeds the thickness of the plate, and a plurality of spaced herringbone walls connecting 100 said parallel walls. 105

4. As an article of manufacture, a grate bar comprising a comparatively deep vertical plate having a transverse notch in its upper edge and having a plurality of laterally projecting spaced teeth, a transverse wall at the upper end of said plate and having a lateral extent exceeding the thickness of said plate and the lateral extent of the teeth, a pair of parallel walls connected to the transverse wall and spaced apart a distance such that the distance between their outer faces exceeds the thickness of the plate, and a plurality of spaced herringbone walls connecting 110 said parallel walls. 115

5. As an article of manufacture, a grate bar comprising a comparatively deep vertical plate having a transverse notch in its upper edge, a transverse wall at the upper end of said plate and having a lateral extent exceeding the thickness of said plate, a pair of parallel walls connected to the transverse wall and spaced apart a distance such that the distance between their outer faces exceeds the thickness of the plate and 125 120

such that the distance between their outer faces is less than the transverse extent of the transverse wall, and a plurality of spaced herringbone walls connecting said parallel walls.

6. As an article of manufacture, a grate bar comprising a comparatively deep vertical plate having a transverse notch in its upper edge and having a plurality of laterally projecting spaced teeth, a transverse wall at the upper end of said plate and having a lateral extent exceeding the thickness of said plate and the lateral extent of the teeth, a pair of parallel walls connected to the transverse wall and spaced apart a distance such that the distance between their outer faces exceeds the thickness of the plate and such that the distance between their outer faces is less than the transverse extent of the transverse wall, and a plurality of

spaced herringbone walls connecting said parallel walls.

7. As an article of manufacture, a grate bar comprising a comparatively deep vertical plate having a transverse notch in its upper edge, a transverse wall at the upper end of said plate and having a lateral extent exceeding the thickness of said plate, a pair of parallel walls connected to the transverse wall and spaced apart a distance such that the distance between their outer faces exceeds the thickness of the plate, and a plurality of spaced walls connecting said parallel walls.

In witness whereof, I have hereunto set my hand at Indianapolis, Indiana, this 27th day of March, A. D. one thousand nine hundred and seventeen.

MAURICE A. HOFFT.
